UNITED STATES PATENT OFFICE.

WILLIAM H. DICKERHOOF, OF CINCINNATI, OHIO.

NON-REFILLABLE BOTTLE.

1,119,931.

Specification of Letters Patent.

Patented Dec. 8, 1914.

Application filed December 9, 1912. Serial No. 735,809.

To all whom it may concern:

Be it known that I, WILLIAM H. DICKERHOOF, a citizen of the United States, residing in Cincinnati, in the county of Hamilton and State of Ohio, have invented certain new and useful Improvements in Non-Refillable Bottles, of which the following is a specification.

My invention relates to novel means for preventing the refilling of bottles.

The object of my invention is to provide simple, economical and efficient means for preventing the filling of a bottle more than once.

My invention consists in the novel means herein set forth and claimed.

In the accompanying drawing which serves to illustrate the construction, and use of my invention: Figure 1 is a vertical section of the neck and upper portion of a bottle having my invention applied thereto. Fig. 2 is a similar view illustrating how the contents of the bottle may be discharged therefrom. Fig. 3 is a side elevation of my 25 tapered, spiral, corrugated non-pull out glass plug. Fig. 4 is a top view of the same, Fig. 5 a bottom view thereof, and Fig. 6 is a side elevation of the elongated valve.

In the embodiment of my invention, as 30 illustrated, and which shows a preferred construction 1 represents a bottle having a neck 2 provided with an inner annular ledge to form a valve seat 3. The neck of the bottle is preferably formed in substantially 35 the shape shown, the opening at the outer end being tapered inwardly as at 4, to receive the tapered spiral, corrugated, glass plug 5, and the ordinary cork or stopper 6. The shape of the opening below the point at 40 which the glass plug 5 seats may be of substantially uniform diameter or of any form or shape desired down to the valve seat 3 and also below said valve seat as shown in the drawing. The interior of the neck of 45 the bottle which engages the glass plug is provided with a ground surface 7. The glass plug is preferably formed with spiral grooves 8, extending from top to bottom, forming spiral ridges 9, the outer surfaces 50 or edges of which are ground to correspond with the surface 7 of the interior of the neck of the bottle. The valve 10, is preferably formed oval shaped or elongated so that it will readily engage the valve seat 3, and 55 close the opening against the passage of liquid inwardly, and will also readily move

out of said seat when the bottle is turned to the position shown in Fig. 2.

When it is desired to seal the bottle constructed in accordance with my invention 60 the liquid is placed therein through the open neck 2, the valve 10 is dropped into position upon the valve seat 3, the glass plug 5 is wedged into the position shown in Fig. 1, the ground surface of the ridges 9 engaging with the ground surface 7 of the bottle and binding said parts tightly and non-removably together after which the ordinary cork 6 is compressed into position as shown in Fig. 1. When it is desired to 70 empty or partly empty the bottle all that is necessary is to remove the cork 6 and turn the bottle to the position shown in Fig. 2, permitting the valve 10 to unseat and the liquid to discharge therefrom and to pass 75 out of the neck of the bottle through the spiral grooves of the glass plug 5. As soon as the bottle is turned to an upright position the valve 10 will automatically seat and assume the position shown in Fig. 1 so that if 80 any effort should be made to refill the bottle by pouring liquid therein it will only pass downwardly through the spiral grooves and be prevented from entering the bottle by the valve 10, thus rendering it impracticable to 85 attempt to use the bottle over again.

By making the grooves spiral the difficulty in removing the glass plug is increased since it would be practically impossible to introduce any instrument through the spiral 90 grooves by which the plug could be disengaged and pulled out. Besides the engagement and wedging together of the ground surface of the bottle and the plug, respectively makes it practicably impossible 95 to disengage the glass plug after it has once been forced into tight engagement with the ground surface 7 of the interior of the neck 2 of the bottle.

The valve seat should be located some 100 distance from the fixed position of the glass plug 5 to permit the valve to readily seat and unseat for the purpose of preventing the passage of liquid into the bottle and to permit it to discharge the liquid from the 105 bottle as the case may be. The valve is considerably smaller in diameter than the diameter of the opening between the valve seat 3 and the plug 5 which permits the liquid when pouring it from the bottle to 110 readily pass said valve.

It will be seen that my invention is one

of great simplicity and one which is adapted to successfully accomplish the desired result of preventing the refilling and re-use of bottles.

5 My invention is capable of some modification without material departure from the scope or spirit thereof.

I claim:

In a non-refillable bottle having an interiorly and inwardly tapered neck with a valve seat therein and a valve seating on said seat, a guard for said valve consisting of a tapered plug with its taper fitting the taper of the neck, said plug being composed 15 of a series of ridges radiating from a common center substantially at the axis of the plug and running spirally with relation to said axis, said ridges having thin edges constituting the taper of the plug and being 20 interrupted throughout said taper, the up-

per ends of said ridges being substantially at right angles to the axis of the plug and being thin, the lower ends of said ridges being inclined to the axis downward to the center where the ridges radiate from, and these lower edges being thin, the surface of said taper of the neck being roughened and the narrow edges of said spiral ridges being roughened to engage with the roughened surface of the neck, said guard being 30 located away from the seat of the valve a distance greater than the length of said valve, and the valve, due to this distance of the guard and due to its formation, being able to entirely leave the region of its seat. 35

WILLIAM H. DICKERHOOF.
